UNITED STATES PATENT OFFICE.

EZEKIEL B. COX, OF NEWTOWN, PENNSYLVANIA.

APPARATUS FOR TREATING GRAIN.

961,068.

Specification of Letters Patent.

Patented June 7, 1910.

Application filed December 23, 1909. Serial No. 534,734.

To all whom it may concern:

Be it known that I, EZEKIEL B. Cox, a citizen of the United States, residing at Newtown, Pennsylvania, have invented certain new and useful Improvements in Apparatus for Treating Grain, of which the following is a specification.

My invention relates to an improved apparatus for ridding grain of all material which is softer than the grain, although it may be of such size and weight as to be incapable of separation by the ordinary methods of screening or scouring.

By my improved apparatus, I subject the grains to a grinding action, which, while of such a character that it will not injure the good and hard kernels of the grain, will grind up or pulverize all garlic and bug-eaten or moth-eaten kernels, reducing them to such a condition that they are readily separated by the ordinary screening or scouring machines.

The invention includes the novel features of construction and arrangement and combination of parts of the apparatus herein-after described and particularly set forth in the appended claims.

A machine constructed in accordance with my invention is illustrated in the accompanying drawings, in which—

Figure 1 is a sectional elevation; Fig. 2 is a plan view; Fig. 3 is an enlarged view of the cut off plate and Fig. 4 is an enlarged cross sectional view through the casing.

Referring by reference characters to these drawings, the numeral 1 designates the uprights of a main upright frame connected at bottom and top by the horizontal members 2 and 3, which, in turn, support the cross bars 4 and 5, the lower one of which carries the step bearing for the lower end of the vertical shaft 6, which carries the rotary parts of the machine as hereinafter described. The shaft 6 is journaled at its upper end in a bearing 7 carried by the bar 5. Supported on suitable uprights 8 within the frame members is a casing 9 which has leading from its lower side a spout 9^a which discharges upon a screen 10 carried by a screen frame 10^a mounted upon vertically disposed flat springs 11 and receiving a longitudinal reciprocating motion through a bar 12 connected to a strap 13 working upon an eccentric 14 on the shaft 6, rotary motion being

imparted to the shaft through a driven pulley 15 to which motion is imparted from any suitable source of power. The casing 9 is provided with a cover plate 16, which is provided with a plurality of openings 16^a, and above this cover plate is rotatably mounted a cut-off plate 17, which is provided with corresponding holes 17^a and a handle 18, by means of which it may be rotated to vary the size of the openings leading into the casing. Within the casing is located a revolving scraper arm 19 which has its hub securely fastened to the shaft 6 by any suitable means, such as a set screw 19^a, and it will be seen that as this scraper blade rotates or revolves within the casing, it will cause any material which has been delivered into the casing and rests upon the bottom thereof to be carried around and discharged through the spout. Above the casing are mounted a plurality of casing rings 20, which are preferably of octagonal cross section. These are mounted the one above the other, and are provided with sets of projecting lugs 20^a, which are engaged by the vertically disposed clamping rods 21. Upon the topmost ring is located a cover plate 22 which is clamped in position by nuts 23 threaded upon the rods 21. These rings thus constitute an internally grooved casing which may be built up to any height according to the character of the work to be performed.

The shaft 6 carries within the casing a disk 24 supported upon an adjustable collar 25, which may be secured in any suitable position by a set screw 26, and above this disk 24 are arranged in alternation disks or plates 27 provided with serrated or toothed edges, and other disks or rings 28 provided with projecting pins 28^a.

The cover plate is provided with the opening 22^a for the admission of the grain, and the shaft 6 carries a rotary plate or frame 32 provided with upwardly projecting distributor teeth 30, which may be arranged in staggered relation to downwardly projecting teeth 31 carried by bars 29 secured to the under side of the cover plate.

From the above description it is thought that the operation of the apparatus will be obvious, but it may be briefly stated as follows: The grain to be treated, such, for instance, as wheat, is fed in through the inlet opening, and distributed by the revolving

teeth on the plate 29, and thence it passes downward upon the topmost plate 27, and is thrown outward by centrifugal action against the rings, and thence passes down 5 between the revolving teeth and the rings, being acted upon by the said teeth and the pins or projections on the disk, which results in grinding up or pulverizing all softer materials, such as garlic or insect-eaten 10 grain, while the hard, sound grains remain unaffected, and are delivered from the machine upon the screen 10 in a whole condition, when they are separated from the pulverized material. By means of the handle 15 18, the discharge openings in the plate 16 may be more or less closed to retain the grain within the casing rings for a sufficient length of time to secure the requisite grinding action, which length of time is readily 20 determined by experience.

Having thus described my invention what I claim is:—

1. In combination a stationary cylindrical casing having a plurality of alternate 25 grooves and ridges on the interior and a rotary grinding device within the casing comprising a plurality of superimposed disks having serrated edges and other disks alternately arranged with respect to the 30 other disks and having pins projecting from their edges, and an inlet to and discharge from said casing.

2. In combination a collecting casing or chamber, a casing surmounting said collecting chamber and composed of a plurality of rings having beveled edges and superimposed upon each other, a shaft journaled in the casing, a grinding device consisting of superimposed disks mounted upon said shaft 40 and having alternately teeth and projecting pins coacting with the inner surface of said rings, a cutoff plate controlling the admission of grain to the collecting casing, a discharge from the collecting casing, and a rotary scraper blade carried by the shaft with- 45

in the collecting chamber, substantially as described.

3. In combination a suitable frame, a collecting casing supported therein above the bottom of the frame and having a suitable 50 discharge outlet at one side, a plurality of rings superimposed above said collecting casing and constituting a grinding casing, a shaft journaled vertically in the frame and passing through said collecting and 55 grinding casing, a scraper plate carried by the shaft within the collecting casing, a plurality of serrated disks carried by the shaft within the grinding casing, a cut-off device for controlling the communication between 60 said casings, and a feed opening for the grain at the upper end of said grinding casing, substantially as described.

4. In combination a suitable frame, a collecting casing supported therein above the 65 bottom of the frame and having a suitable discharge outlet at one side, a plurality of rings superimposed above said collecting casing and constituting a grinding casing, a shaft journaled vertically in the frame 70 and passing through said collecting and grinding casing, a scraper plate carried by the shaft within the collecting casing, a plurality of serrated disks carried by the shaft within the grinding casing, a cut-off device 75 adapted to control the communication between said casings, and a feed opening for the grain at the upper end of said grinding casing, a screen adapted to receive the discharge from the collecting casing, and 80 means whereby said screen receives reciprocating motion from the vertical shaft, substantially as described.

In testimony whereof, I affix my signature in presence of two witnesses.

EZEKIEL B. COX.
